Attorney

UNITED STATES PATENT OFFICE.

WALTER A. RARIG, OF OAKLAND, CALIFORNIA.

OILER FOR ENGINES.

Application filed December 1, 1917, Serial No. 204,926. Renewed March 26, 1923.

To all whom it may concern:

Be it known that I, WALTER A. RARIG, citizen of the United States, residing at Oakland, in the county of Alameda and State of California, have invented certain new and useful Improvements in Oilers for Engines, of which the following is a specification.

This invention is an improved oiling device for use on Ford automobile engines.

The principal object of the invention is to provide an oiling device which will circulate the oil through the casing of the engine by catching the oil as it is thrown by centrifugal force by the generator at its highest point and carrying it forward by gravity and introducing it in the forward part of the casing.

When an automobile ascends a grade the tendency is to drain the forward cylinders of their lubricating oil as the pitch of the engine causes it to gravitate toward the rear. This results in overheating, smoke, and like annoyances.

Obviously a device which will deliver a uniform flow of oil to the front cylinders, regardless of grade, will result in increased efficiency of the engine and effect a saving in wear.

A further object of the invention is to make an oil conduit of such construction that it can be easily and quickly attached to Ford engines and which, when installed, may be inspected without removal of any of the parts.

These objects are fully accomplished in the novel structure described in the following specification and illustrated in the accompanying drawings, in which—

Figure 1 is a view of my oiling device installed on a Ford engine, the engine being shown in dotted lines and here shown only to illustrate the method of attachment.

Figure 2 is a front view of a sight feed oil cup casting.

Figure 3 is a rear view of same.

Figure 4 is a side view of same with a glass attached, a portion being broken away and shown in section.

Figure 5 is a side view of these component parts of my improved oiling device which are forward of the sight feed oil cup.

Figure 6 is a side view of those parts which are on the opposite side of the oil cup from that of the parts shown in Figure 5.

Referring to the drawings, 1 indicates a base of an engine casing sloping rearwardly to a sump 2 in an enlarged annular portion of the housing in which rotates a generator. A hole 3 is drilled in the upper portion 4 of the said annular member of the housing. The hole 3 is tapped to receive the threaded end of the bushing 6.

The bushing 6 is provided with a cup-shaped deflector 7 on the inside projecting into the annular cavity to deflect oil as it is thrown centrifugally by the generator.

Into the bushing 6 is screwed one end of an elbow 8 the opposite end of which is threaded into a union 9 on one end of a pipe 11.

The opposite end of pipe 11 is threaded into an oil cup casting 12. The said casting 12 is substantially two elbows cast integrally to form respectively intake and outlet for a cell of glass 13.

The inner openings of the elbows are diametrically opposed so that, when the cell 13 is placed in horizontal position, as in Fig. 1, the intake port 14 will be above the outlet port 16.

The face of the casting 12 is provided with an annular groove 17, Fig. 2, in the bottom of which is a gasket 18 of cork or suitable material. The glass 13 is secured within the groove 17 and held against the gasket 18 by a bolt 19 threaded into a hole in the center of the casting 12 as shown at 21, Fig. 4.

A rubber washer 22 is placed between the head of bolt 19 and the lower edge of the glass 13.

A short piece of pipe 23 is threaded into the intake port 14 so that the flow of oil will be more visible.

As the oil is thrown into the cell it gravitates through outlet port 16 into a pipe 26 connected therewith at one end and at its opposite end to a union 27 on one end of a nipple 28 the opposite end of which is threaded into a hole in a flattened surface 29 on a hexagonal post 31.

The post 31 has a hollow passage 32 for continuation of the conduit. A reduced member 33 of post 31 is threaded to enter a bolt hole 34, Fig. 1.

In order to facilitate installation I connect the member 33 of post 31 to a forward hole of a series of bolt holes in which are bolts to secure the upper and lower mem-

bers of the engine casing, so in installing my device it is necessary only to drill one hole (3) and tap two (3 and 34).

What I claim as new and wish to cover 5 by Letters Patent is:

1. A sight glass of the character described, comprising a plate having an inlet and an outlet opening therein, a transparent tubular member having one end fitted against one 10 face of the plate and having said openings communicating therewith, a cap closing the other end of said tube, and a connecting rod detachably connecting said cap and plate together, whereby the parts are maintained 15 in position.

2. A sight glass of the character described, comprising a plate having an annular groove in one face thereof and inlet and outlet openings in said face and surrounded by 20 said groove, a gasket in said groove, a transparent cup-shaped member having its edge resting in said groove and upon the gasket, and a member extending through the closed end of the cup member and having engagement 25 with said plate, whereby the parts are maintained in position.

3. In a device of the character described, a casting comprising a vertically arranged plate and an inlet opening and an outlet 30 passage, said passages opening through the face of said plate, and arranged one over the other respectively, a transparent cap detachably secured to the casting and closing both of said openings and spaced from the 35 latter.

4. The combination with an internal combustion engine which includes a generator housing, of an oil deflector extending substantially radially through the upper part 40 of the periphery of said housing a short distance into the housing, an indicator and a circulating pipe connected with said deflector to convey oil from said housing to said indicator and then to the forward end 45 of the engine casing.

5. In a lubricating system for internal combustion engines wherein an engine is provided with a horizontal crank shaft at one end of which a fly-wheel is positioned 50 having radially disposed magneto magnets secured to one of its side faces; said fly-wheel and crank-shaft being enclosed within a housing partially filled with oil, the combination with said engine, of an oil receiving 55 stem disposed through the side of the housing in alignment with the axial path of travel of the magnets and spaced therefrom, and a circulating pipe connected with said stem to convey the oil thrown by the magnets 60 to an indicator and then to the forward end of said housing.

6. In a lubricating system for internal combustion engines of the class described, a tubular stem extending through the side of the fly-wheel housing of said engine and adapted to present an oil inlet opening to the oil thrown by centrifugal force from the radially disposed magnets upon the face of the fly-wheel of said engine and to stand in axial alignment therewith and spaced 70 from said magnets, an elevating tube in connection with said stem and through which the oil will be forced by the motion of said magnets, a sight feed through which the oil will pass, and a circulating tube in connection with said sight feed to convey the oil to the forward end of the engine crank case. 75

7. A lubricating system for engines, comprising an oil receiving stem formed with an opening in its side in communication with a longitudinal bore leading to the opposite end of the stem, said stem being positioned through the fly-wheel and magneto case of said engine and in direct alignment with magnets upon the fly-wheel, said oil receiving stem being spaced from said magnets, and disposed through the side of the case to stand within the path of travel of oil thrown upwardly by the centrifugal force of said moving magnets, a sight feed with which said stem communicates, and a circulating pipe conveying the oil from the sight feed to the forward end of the engine where it is caused to pour over the timing gears and to thereafter circulate through 90 the engine crank case.

8. A device of the character described, comprising a plate having an inlet and an outlet opening therein, a member having one end fitted against one face of the plate 100 and having said openings communicating therewith, a cap closing the other end of said member, and a connecting rod detachably connecting said cap and plate, whereby the parts are maintained in position. 105

9. In a lubricating system for internal combustion engines of the class described, a tubular stem extending through the side of the fly-wheel housing of said engine and adapted to present an oil inlet opening to the oil thrown by centrifugal force from the radially disposed magnets upon the face of the fly-wheel of said engine and to stand in axial alignment therewith and spaced from said magnets, an elevating tube in connection with said stem and through which the oil will be forced by the motion of said magnets, and a circulating tube to convey the oil to the forward end of the engine crank case. 110

In testimony whereof I affix my signature.
WALTER A. RARIG.
